UNITED STATES PATENT OFFICE.

JOSEPH CUNNINGHAM, OF SOUTH BETHLEHEM, PENNSYLVANIA.

MAIL-CARRIER.

1,260,877.

Specification of Letters Patent. Patented Mar. 26, 1918.

Application filed January 3, 1918. Serial No. 210,120.

To all whom it may concern:

Be it known that I, JOSEPH CUNNINGHAM, a citizen of the United States, residing at South Bethlehem, in the county of Northampton, State of Pennsylvania, have invented new and useful Mail-Carriers; and I do hereby declare the following to be a full, clear, and exact description of the invention, such as will enable others skilled in the art to which it appertains to make and use the same.

The present invention relates to a rural route mail carrier, and has for its object to provide a device of this character which embodies novel features of construction whereby the mail box is mounted to be moved back and forth between the house and the road, thereby avoiding unnecessary trips to the road for the purpose of depositing mail or ascertaining if anything has been left by the postman.

Further objects of the invention are to provide a rural route mail carrier which is comparatively simple and inexpensive in its construction, which can be easily installed, which can be easily and quickly manipulated to move the box back and forth between the road and the house, and which is so constructed as to render it impossible for the mail to be lost from the box at an intermediate point in the travel thereof.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of a rural route mail carrier constructed in accordance with the invention, the mail box and supporting hanger being shown as positioned at an intermediate point in the length of the track.

Fig. 2 is an enlarged view of the mail box and hanger with the hanger partly broken away and the box in transverse section, parts being broken away and the door of the box

being shown by dotted lines as swung outwardly.

Fig. 3 is a side elevation of the hanger and upper portion of the box, the box appearing in longitudinal section and being shown by dotted lines as tilted into an angular position for releasing the latch controlling the door.

Corresponding and like parts are referred to in the following description and indicated in all the views of the drawings by the same reference characters.

Referring to the drawings, which illustrate one embodiment of the invention, the numeral 1 designates a bracket plate which is designed to be rigidly secured at a suitable elevation to some portion of the house by suitable fastening members such as the screws 2. The upper edge of the bracket plate is formed with an outstanding horizontal wing 3, and immediately below the said wing a vertically disposed grooved wheel 4 is journaled between a pair of outstanding arms 5. Secured to a post 6 or similar supporting member at a convenient point adjacent to the road, is a bracket plate 7 which has a vertically elongated formation, the upper end thereof being provided with an outstanding horizontal wing 8 and a pair of arms 9 between which a grooved wheel 10 is journaled. This elongated bracket plate is designed to be secured to the post 6 by suitable fastening members 11 with the wing 8 at the upper end thereof positioned as nearly as possible in a horizontal plane with the corresponding wing 3 of the plate 1.

A cable track 12 connects the wing 3 of the plate 1 and the wing 8 of the plate 7, said track being stretched taut and each end thereof securely fastened to the wing of the respective plate. An endless cable 13 is arranged immediately below the track 12 and passes around the two grooved guide wheels 4 and 10. A hanger 14 is provided with a grooved wheel 15 which travels upon the track 12, the upper end of the hanger being returned at 14^a and the wheel being arranged between the said returned portion of the hanger and the body of the hanger.

The lower end of the hanger terminates in an inwardly offset cam extension which is pivotally mounted upon a pin 17 connecting the spaced upstanding ears 18 of a plate 19 which is secured to the top of the mail box 20. The lower end of the cam extension 16 normally projects slightly into the top of the box through a slot 21 provided between the ears 18. The upper reach of the endless cable 13 is secured to the hanger 14 by means of a fastener 22, while the lower reach of the cable may pass loosely through a guide eye 23 provided at one end of the pivot pin 17, thereby preventing it from rubbing 15 against the sides of the box. With this construction it will be obvious that by manipulating the endless cable 13 the mail box can be caused to travel back and forth upon the track 12 between the house and the road.

20 In the particular embodiment of the invention which has been illustrated, the door 24 of the box closes the front thereof, being hinged at 25 to the bottom of the box. The swinging end of the door is shown as provided with a keeper 26 adapted to be engaged by the nose of a spring latch 27 which projects from the back of the box. This latch member extends across the slot 21 and the resiliency thereof normally tends to 25 swing the nose of the latch upwardly into an inoperative position so as to disengage it from the keeper 26 and permit the door 24 to be opened. However, as long as the box hangs freely from the track and is in an up- 30 right position, the lower end of the cam extension 16 of the hanger engages the latch member 27 to flex the same downwardly and hold the same in operative position, as indicated by Fig. 2. When it is desired to open 35 the mail box it is merely necessary to swing the latter into an angular position about the pivot pin 17 as a center, as indicated by dotted lines on Fig. 3. The latch member 27 will then be swung away from the cam 40 extension 16, whereupon it will disengage itself from the keeper 26 and permit the door 24 to be opened. The door 24 can thus be very rapidly opened, although there is no danger of the door accidentally swinging 45 open and permitting the mail to be lost while the box is being moved from one end of the track to the other end thereof.

Having thus described my invention, what I claim as new and desire to secure by 50 Letters Patent, is:

1. A rural route mail carrier, including a pair of vertically disposed bracket plates rigidly mounted at a distance apart, each of the plates having a horizontal wing at 55 its upper end and being provided immediately below the wing with a pair of outstanding arms, guide wheels journaled between the outstanding arms of the bracket plates, a cable track stretched between the

wings of the two plates, an endless cable 65 passing around the guide wheels, a hanger provided with a grooved wheel mounted to travel upon the track, and a box suspended from the hanger, the endless cable being connected to the hanger for moving the same 70 back and forth upon the track.

2. A rural route mail carrier, including a pair of bracket plates mounted at a distance apart, a cable track stretched between the bracket plates, guide wheels carried by the bracket plates, an endless cable extending around the guide wheels and arranged immediately below the track, a hanger provided with a grooved wheel adapted to engage the track, a box suspended from the hanger, and guide means on the hanger for loosely engaging one reach of the endless cable, the other reach thereof being secured to the hanger for moving the hanger back and forth upon the track.

3. A rural route mail carrier, including a pair of bracket plates rigidly mounted at a distance apart, a cable track stretched between the bracket plates, guide wheels carried by the bracket plates, an endless cable 90 extending around the guide wheels and arranged immediately below the track, a hanger provided with a grooved wheel adapted to travel upon the track, a box suspended from the hanger, and a pivot pin 95 connecting the box to the hanger and having a guide eye at one end thereof which loosely receives one reach of the endless cable, the other reach of the endless cable being secured to the hanger for moving it 100 back and forth upon the track.

4. A rural route mail carrier, including an elevated track, a hanger provided with a grooved wheel adapted to travel upon the track, a box suspended from the hanger and pivotally connected thereto, a door for the box, and a door latch controlled by the swinging movements of the box about its pivotal connection with the hanger.

5. A rural route mail carrier, including an elevated track, a hanger provided with a grooved wheel adapted to travel upon the track and terminating at its lower end in a cam extension, a box pivotally connected to the hanger and pendent therefrom, a door for the box, and a door latch engaged by the cam extension of the hanger and arranged to be released thereby when the box is swung into an angular position with respect to the hanger.

6. A rural route mail carrier, including an overhead track, a hanger provided with a grooved wheel adapted to travel upon the track and terminating at its lower end in a cam extension, a box pivotally suspended from the hanger and provided with an opening receiving the cam extension, a door for the box, and a resilient door latch extending

across the opening of the box so as to be engaged by the cam extension of the hanger, the door latch being held in operative position while the box hangs in an upright position, being released when the box is tilted into an angular position with respect to the hanger.

In testimony whereof I have signed my name to this specification in the presence of two subscribing witnesses.

JOSEPH CUNNINGHAM.
